UNITED STATES PATENT OFFICE.

ANTHONY BIZZARRI, OF NEW YORK, N. Y., ASSIGNOR, BY MESNE ASSIGNMENTS, TO
SPECIALTY PATENTS HOLDING CO., INC., OF NEW YORK, N. Y., A CORPORATION OF NEW YORK.

DESIGN FOR AN AUTOMOBILE BODY.

Application filed July 2, 1926. Serial No. 18,232. Term of patent 3½ years.

To all whom it may concern:

Be it known that I, ANTHONY BIZZARRI, a subject of the King of Italy, and resident of New York city, in the county and State of New York, and whose post-office address is 141 West 54th Street, New York city, have invented a new, original, and ornamental Design for an Automobile Body, of which the following is a specification, reference being had to the accompanying drawing, forming part thereof.

The figure is a perspective view of an automobile body showing my new design.

I claim:

The ornamental design for an automobile body as shown.

ANTHONY BIZZARRI.
